UNITED STATES PATENT OFFICE.

WILLIAM MATHER, OF SALFORD IRON WORKS, MANCHESTER, COUNTY OF
LANCASTER, ENGLAND.

APPARATUS FOR TREATING TEXTILE FABRICS.

SPECIFICATION forming part of Letters Patent No. 402,757, dated May 7, 1889.

Application filed January 31, 1889. Serial No. 298,228. (No model.) Patented in England November 24, 1886, No. 15,343.

To all whom it may concern:

Be it known that I, WILLIAM MATHER, engineer, a citizen of England, residing at Salford Iron Works, Manchester, in the county of Lancaster, England, have invented a new and useful Improvement in Apparatus for Treating Textile Materials with Liquids, Gases, or Vapors, (which has been partly patented to me in Great Britain by Patent No. 15,343, dated November 24, 1886,) of which the following is a specification.

In my patent dated August 4, 1885, No. 323,819, and in my later patent, dated January 5, 1886, No. 333,876, I described apparatus for treating textile materials with liquids, gases, or vapors for various purposes, such as soaking, boiling, or dyeing. That apparatus consisted of a keir or vessel like a horizontal cylindrical boiler closed at either end or at each end by a wedge sluice-door, and having in it rails to receive trucks containing the material to be treated, and pipes for supply, discharge, and circulation of the fluids to the action of which the material in the trucks was subjected. I described the trucks to be of lattice construction, giving passage for the fluids through their bottoms and sides. I also in my later patent, No. 333,876, described each truck as being made with an internal 25 perforated chamber which was put in communication with a longitudinal pipe in the lower part of the keir by means of a spring junction-pipe attached to the bottom of the truck, which junction-pipe, when the truck was run into position in the keir, came into 30 coincidence with an aperture in the upper side of the longitudinal pipe.

My present invention relates to a construction of each truck with close sides and with a perforated floor having under it a chamber, which is put in communication with the keir-pipe in the same manner as the internal chambers of the trucks previously described. By dispensing with the internal chamber I leave 45 the whole capacity of the truck free to receive the yarns or fabrics that are to be treated. I also simplify and cheapen the construction of the truck, and by the use of a floor perforated all over I provide for the uniform passage of the fluids employed either up through 50 the material in the truck when the fluids are

supplied from below, or down through the material when the fluids are supplied from sprinklers above the trucks.

I shall describe the construction of trucks 55 according to my present invention, referring to the accompanying drawings.

Figure 1 is a longitudinal section of the keir with two trucks placed in it. Fig. 2 is a transverse section. 60

The keir A, which is in form like a horizontal cylindrical boiler, may be made of greater or less length, according to the number of trucks that are to be accommodated in it. Practically, I find it is conveniently made 65 to accommodate two trucks, as shown in Fig. 1, and to have a wedge sluice-door B, at one end only, the other end being permanently closed. The apparatus for opening and tightly closing the door B forms the subject of an 70 other application for Letters Patent of even date with the present, and therefore I need not here describe that apparatus.

Each truck C consists of a shell, D, of iron or steel plate, preferably galvanized or otherwise coated to protect the material in the truck from being stained by oxide. The ends of the truck are vertical, the bottom is flat, and the sides are bent to a curvature concentric with that of the keir A, but of smaller 80 radius, so as to leave a space of several inches between them and the interior surface of the keir. The top of the truck is open. From the center of the bottom of the truck depends the spring junction-pipe E, which, as described in my former patent, No. 333,876, 85 forms a communication from the fixed pipe F through the bottom of the truck. A little above the bottom plate of the truck is fixed a distributing-plate, G, having through it 90 numerous perforations, and on this plate is laid an open floor or grating of transverse timbers H and longitudinal timbers K, on which are placed the materials to be treated.

The truck is mounted on four wheels, L, 95 which run on rails M, laid in the bottom of the keir in line with external rails, so that when the sluice-door B is raised folding rails N can be let down to join the internal to the external rails, and the trucks can be run into 100 the keir or out of it. In the bottom of the keir, besides the central pipe, F, there are

steam-pipes S, for heating, and perforated steam-pipes S', for blowing steam into the keir. At the top of the keir are sprinklers P, by which liquid can be distributed over the contents of the trucks. These, as well as the pipe F, are connected to the suction and discharge of a rotary or other pump by branches provided with valves, so that liquid can be sent to the sprinklers P and drawn off from the pipe F or run off by a blow-off pipe Q, or that liquid can be sent through the pipe F up through the materials in the trucks, so as to overflow and escape by the pipe Q.

Having thus described the nature of my invention and the best means I know of carrying it out in practice, I claim—

In apparatus for treating textile materials with liquids, gases, or vapors, consisting of a

keir containing trucks charged with the materials, a truck made as a shell of metal plate with open top, vertical ends, imperforate curved sides, and a perforated distributing bottom plate with a compartment below it having a spring junction-pipe, substantially as described. 20 25

In testimony whereof I have signed my name to this specification, in the presence of two subscribing witnesses, this 12th day of January, A. D. 1889.

W. MATHER.
